CLAIM

The ornamental design for a combined ball throwing and drinking device, as shown and described.

DESCRIPTION

FIG. 1 is a perspective view of a combined ball throwing and drinking device showing the new design;

FIG. 2 is a top plan view thereof;

FIG. 3 is a bottom plan view thereof;

FIG. 4 is a front elevation view thereof;

FIG. 5 is a rear elevation view thereof; and,

FIG. 6 is a right side elevation view thereof, the left side being a mirror image of the same.
